(57) **CLAIM**

The ornamental design for an organizer system and components of the organizer system, as shown and described.

DESCRIPTION

FIG. 1 is a top left front perspective view of a first design for a first organizer of an organizer system, with a cover of the first organizer in a closed position;

FIG. 2 is a front view of the first design for the first organizer of the organizer system, with the cover of the first organizer in the closed position;

FIG. 3 is a rear view of the first design for the first organizer of the organizer system, with the cover of the first organizer in the closed position;

FIG. 4 is a left side view of the first design for the first organizer of the organizer system, with the cover of the first organizer in the closed position;

FIG. 5 is a right side view of the first design for the first organizer of the organizer system, with the cover of the first organizer in the closed position;

FIG. 6 is a top view of the first design for the first organizer of the organizer system, with the cover of the first organizer in the closed position;

FIG. 7 is a bottom view of the first design for the first organizer of the organizer system, with the cover of the first organizer in the closed position;

FIG. 8 is a top left front perspective view of a second design for the first organizer of the organizer system, with the cover of the first organizer in an example open position;

FIG. 9 is a front view of the second design for the first organizer of the organizer system, with the cover of the first organizer in the example open position;

FIG. 10 is a rear view of the second design for the first organizer of the organizer system, with the cover of the first organizer in the example open position;

FIG. 11 is a left side view of second design for the first organizer of the organizer system, with the cover of the first organizer in the example open position;

FIG. 12 is a right side view of the second design for the first organizer of the organizer system, with the cover of the first organizer in the example open position;

FIG. 13 is a top view of the second design for the first organizer of the organizer system, with the cover of the first organizer in the example open position;

FIG. 14 is a bottom view of the second design for the first organizer of the organizer system, with the cover of the first organizer in the example open position;

FIG. 15 is a top left front perspective view of a third design for the first organizer of the organizer system, the third design having the same front view of FIG. 9, rear view of FIG. 10, left side view of FIG. 11, right side view of FIG. 12, and bottom view of FIG. 14, with the cover of the first

organizer in the example first open position of FIGS. 8-14 and including removable organizers disposed in the first organizer;

FIG. 16 is a top view of the third design for the first organizer of the organizer system, the third design having the same front view of FIG. 9, rear view of FIG. 10, left side view of FIG. 11, right side view of FIG. 12, and bottom view of FIG. 14, with the cover of the first organizer in the example first open position of FIGS. 8-14 and including removable organizers disposed in the first organizer;

FIG. 17 is a top right perspective view of a first design for a first removable organizer of the organizer system, with a cover of the first removable organizer in a closed position;

FIG. 18 is a front view of the first design for the first removable organizer of the organizer system, with the cover of the first removable organizer in the closed position;

FIG. 19 is a rear view of the first design for the first removable organizer of the organizer system, with the cover of the first removable organizer in the closed position;

FIG. 20 is a left view of the first design for the first removable organizer of the organizer system, with the cover of the first removable organizer in the closed position;

FIG. 21 is a right view of the first design for the first removable organizer of the organizer system, with the cover of the first removable organizer in the closed position;

FIG. 22 is a top view of the first design for the first removable organizer of the organizer system, with the cover of the first removable organizer in the closed position;

FIG. 23 is a bottom view of the first design for the first removable organizer of the organizer system, with the cover of the first removable organizer in the closed position;

FIG. 24 is a top right perspective view of a second design for the first removable organizer of the organizer system, with the cover of the first removable organizer in an example open position;

FIG. 25 is a front view of the second design for the first removable organizer of the organizer system, with the cover of the first removable organizer in the example open position;

FIG. 26 is a rear view of the second design for the first removable organizer of the organizer system, with the cover of the first removable organizer in the example open position;

FIG. 27 is a left view of the second design for the first removable organizer of the organizer system, with the cover of the first removable organizer in the example open position;

FIG. 28 is a right view of the second design for the first removable organizer of the organizer system, with the cover of the first removable organizer in the example open position;

FIG. 29 is a top view of the second design for the first removable organizer of the organizer system, with the cover of the first removable organizer in the example open position;

FIG. 30 is a bottom view of the second design for the first removable organizer of the organizer system, with the cover of the first removable organizer in the example open position;

FIG. 31 is a top right perspective view of a first design for a second removable organizer of the organizer system, with a cover of the second removable organizer in a closed position;

FIG. 32 is a front view of the first design for the second removable organizer of the organizer system, with the cover of the second removable organizer in the closed position;

FIG. 33 is a rear view of the first design for the second removable organizer of the organizer system, with the cover of the second removable organizer in the closed position;

FIG. 34 is a left view of the first design for the second removable organizer of the organizer system, with the cover of the second removable organizer in the closed position;

FIG. 35 is a right view of the first design for the second removable organizer of the organizer system, with the cover of the second removable organizer in the closed position;

FIG. 36 is a top view of the first design for the second removable organizer of the organizer system, with the cover of the second removable organizer in the closed position;

FIG. 37 is a bottom view of the first design for the second removable organizer of the organizer system, with the cover of the second removable organizer in the closed position;

FIG. 38 is a top right perspective view of the second design for the second removable organizer of the organizer system, with the cover of the second removable organizer in an example open position;

FIG. 39 is a front view of the second design for the second removable organizer of the organizer system, with the cover of the second removable organizer in the example open position;

FIG. 40 is a rear view of the second design for the second removable organizer of the organizer system, with the cover of the second removable organizer in the example open position;

FIG. 41 is a left view of the second design for the second removable organizer of the organizer system, with the cover of the second removable organizer in the example open position;

FIG. 42 is a right view of the second design for the second removable organizer of the organizer system, with the cover of the second removable organizer in the example open position;

FIG. 43 is a top view of the second design for the second removable organizer of the organizer system, with the cover of the second removable organizer in the example open position; and,

FIG. 44 is a bottom view of the second design for the second removable organizer of the organizer system, with the cover of the second removable organizer in the example open position.

The features shown in broken lines depict environmental structure only and form no part of the claimed design.
